WORK GUIDE OR SUPPORT

Francis Low Brandt, Wakefield, Mass., assignor
to United Shoe Machinery Corporation, Paterson, N. J., a corporation of New Jersey

Application May 12, 1932, Serial No. 610,922

18 Claims. (Cl. 144—93)

This invention relates to work guides or supports and is illustrated herein as embodied in a machine particularly adapted for forming holes in shoe bottoms. Another form of such a machine, a species under the present invention, is the subject of an application for Letters Patent filed in my name in the United States Patent Office on December 30, 1935, Serial No. 56,733.

In United States Letters Patent No. 1,615,258, granted January 25, 1927 on application of M. V. Bresnahan there is described a method of temporarily attaching wood heels to shoes by passing a screw fastener through a hole in the rear end of a last within a shoe and through a hole in the heel-seat portion of the shoe bottom into a heel. This secures the last, the shoe and the heel together so that various operations can be performed upon the heel or the shoe without waiting for the heel-attaching adhesive to dry. This method has gone into extensive use and under most conditions is satisfactory. Sometimes, however, the attaching face of the heel and the heel seat of the shoe are not held in close engagement because of the fact that the operator did not apply sufficient preliminary clamping pressure, thus leaving a space between the heel seat and the opposed surface of the heel. When the screw fastener is inserted in such a shoe, the heel seat and the attaching face of the heel cannot be brought into close engagement without considerable difficulty, because the fastener first cuts threads in the wall of the hole formed in the shoe bottom and then cuts threads in the walls of the hole formed in the wood heel.

To avoid this difficulty it has been proposed to form a hole in the shoe bottom of a larger diameter than the diameter of the screw fastener to allow sufficient clearance between the walls of the hole and said fastener. Since the hole in the last bottom must be in alignment with the hole in the last, the drill used to form the clearance hole must be of a length sufficient to pass through the last and through the shoe bottom. The long drill operating at a high speed is dangerous to the operator because of the chance of injury through accidental contact with it. Furthermore, in order to avoid injury to the shoe and last, it is important that they be properly positioned before movement into co-operation with the drill or other operating tool. An object of this invention, therefore, is to provide means for guarding the tool and for guiding or supporting such a work piece as a shoe relatively to said tool so that the operator cannot move the work guide or support

from its inactive position until the work is positioned correctly with respect to the tool.

In accordance with this object one feature of the invention resides in a guide or support movable by work applied to it and means releasable by the work for locking the support against such movement. The movement of the guide may be into co-operation with such an operating tool as a drill, and said guide may furnish a guard for the drill. When shoes on lasts are operated upon, the last cones may enter between opposite guard members, first releasing the lock and then moving the guide longitudinally of the drill. As illustrated, the work guide is mounted on a slide which is provided with a slot or recess to receive a locking member, the locking member being constructed and arranged to be released by contact with the work of a releasing member mounted on the support.

Other objects and features of the invention will be explained in the following description, reference being made to the accompanying drawing in which

Fig. 1 is a view in side elevation of a machine illustrating one embodiment of the invention, showing the work-positioning members and their relation to the drill prior to the hole-forming operation; and

Fig. 2 is an enlarged detail view of a part of the machine, showing the work-positioning members and their relation to the drill at the conclusion of the hole-forming operation.

The machine therein shown has a drill 10 and a movable work guiding or positioning support 12. The drill 10 is rigidly secured to one end of the armature shaft of an electric motor 14 by means of a chuck 16 which is rigidly secured to the shaft by a set screw 18. The machine is mounted on an inclined surface of the base 20 so that the shaft of the motor is inclined downwardly to facilitate positioning a lasted shoe 22 on the work support.

The work support 12 is slidably mounted on a bracket 24 which is secured to the base 20 by screws 26. The upper end of the bracket 24 is provided with an opening to receive a slide 28 to one end of which the support 12 is rigidly secured by a set screw 30. The slide 28 and the work support 12 are normally maintained in the position shown in Fig. 1 by a spiral spring 32. This spring surrounds a spindle 34 mounted on the forward end of the bracket 24 and has its free end secured to the rear of the slide. A stop 36 upon the slide limits its forward movement. To reduce friction, the slide 28 rides on rolls sur-

- rounding the spindle 34 at opposite sides of the spring 32 and on the roll 38, while its upper surface bears against rollers 40 which are mounted in the upper portion of the bracket 24.
- 5 To insure that the lasted shoe is properly positioned relatively to the drill 10 and to prevent injury to the operator, the work support 12 is provided with forwardly extending flanges or guards 42, 44 which are so arranged that the 10 cone of a last 46 can be placed between them. These guards extend beyond the end of the drill 10, thus preventing engagement of the last 46 or of the shoe 22 with the drill before the last hole has been alined with said drill. Between the 15 guards the work presents a plane surface extending transversely of the drill. With this the end of the last cone may contact and thus determine the angular position of the last with respect to the drill.
- 20 To prevent movement of the support 12 until the last 46 and the shoe 22 are properly positioned, a device is provided for locking said support normally in its inactive position. This locking device has a releasing member 48, which is 25 illustrated herein as a finger, pivoted to the work support 12. The finger is normally held with its upper end extending into the space between the two guards 42, 44 by a spring 45. The location of the finger 48 between the guards is such that it 30 cannot inadvertently be moved to disengage the locking device. A releasing bar 50 is connected to the finger by a pin 52. The free end of the bar is arranged for engagement with a cam surface 54 formed on a locking member 56 which is pivoted at 58 to the bracket 24. The bar 50 slides in a guideway formed in the top of the bracket and rests on the rolls 40. A notch 60 is formed in the upper surface of the slide 28 and an end portion of the locking member 56 enters the 40 notch to prevent movement of the support 12 before the finger 48 has been moved rearwardly.

The manner of using the support will now be briefly described. The shoe 22 on the last 46 is placed between the guards 42, 44 forming a part 45 of the work guide or support 12 and its slide 28, the hole in the last being guided thereby into alinement with the drill 10. The shoe is then moved rearwardly until the cone of the last moves the finger 48 rearwardly, thus causing the end of 50 the bar 50 to engage the cam surface 54 on the locking member 56. This rotates the member in a counterclockwise direction, thereby moving the end of the locking member 56 out of the notch 60 in the slide 28. With the parts of the device 55 thus related, continued movement of the shoe will cause the work support to be moved rearwardly until the drill 10 passes through the shoe bottom. When the pressure of the last on the support 12 is released, the support 12 is returned to 60 its original position by the spring 32. Here the end of the member 56 falls into the notch 60, thereby again locking the parts.

Although the invention has been illustrated and described as embodied in a machine for forming 65 holes in shoe bottoms, the invention is not limited thereto, but may be used for other purposes.

Having thus described my invention, what I claim as new and desire to secure by Letters Patent of the United States is:

- 70 1. In a machine for operating upon shoes, the combination of an operating tool, a work support movable to present work to the tool for the operation upon it, means for normally locking the work support positively against such work 75 presenting movement, and means engageable by

work upon the support for directly releasing the locking means simultaneously with the positioning of work upon the support.

2. A machine for operating upon shoes having, in combination, a movable work support, a slide 5 on which said work support is mounted, means adapted to engage the slide for normally locking the work support against movement, and a releasing member engageable by a work piece upon the support for releasing the locking means. 10

3. A machine for operating upon shoes having, in combination, a bracket, a slide mounted on said bracket, a work support rigidly secured to said slide, means pivotally mounted on the bracket and arranged to engage the slide for normally 15 locking the work support against movement, and means engageable by work upon the support for releasing the locking means.

4. A machine for operating upon shoes having, in combination, a movable work support, guards 20 secured to said work support and arranged to permit the cone of a last to be inserted between them, a lock for securing the work support against movement, and means located between the guards and adapted to be engaged by the 25 last upon the support for releasing the lock.

5. A machine for operating upon shoes having, in combination, an operating tool, a bracket fixed relatively to the operating tool, a work support arranged for movement on said bracket, means 30 secured to the bracket and arranged normally to lock the work support against movement, and means engageable by work upon the support for releasing the locking means.

6. A machine for operating upon shoes having, 35 in combination, an operating tool, a bracket, a slide mounted on said bracket, a work support rigidly secured to said slide, means pivotally mounted on the bracket and arranged to engage the slide for normally locking the work support against movement, and means engageable by work upon the support for releasing the locking means. 40

7. A machine for operating upon shoes having, in combination, an operating tool, a work support 45 movable relatively to said tool, guards secured to said work support and arranged to permit the cone of a last to be inserted between them, a lock constructed and arranged to secure the work support against movement, and means 50 located between the guards and adapted to be engaged by the last upon the support for releasing the lock.

8. A machine for operating upon shoes having, in combination, an operating tool, a bracket, a slide 55 mounted on said bracket, a work support rigidly secured to said slide, a lock pivotally mounted on the bracket and arranged to engage the slide for normally locking the work support against movement, and a finger mounted on the 60 work support and engageable by work upon the support for releasing the lock.

9. A machine for operating upon shoes having, in combination, a drill, a work support movable relatively to the drill and arranged to be moved 65 manually toward the drill, a lock arranged for normally holding the work support against movement, a pair of guards mounted on the work support above and below the drill and projecting beyond the end of the drill when the 70 work support is in inactive position, and a releasing finger mounted below the drill and between said guards, said finger being arranged to be engaged by the work upon the support for releasing the lock. 75

10. A machine for operating upon shoes having, in combination, an operating tool, a bracket, a slide mounted on said bracket, a work support rigidly secured to said slide, a locking member 5 pivotally mounted on the bracket and arranged to engage the slide for normally locking the work support against movement, a releasing member engageable by work upon the support for releasing the locking means, and a spring arranged 10 to return the support to inoperative position.

11. A machine for operating upon shoes having, in combination, a drill, a work support movable relatively to the drill and arranged to be moved manually toward the drill, means arranged for 15 normally locking the work support against movement, a pair of guards mounted on the work support above and below the drill and normally projecting beyond the end of the drill when the work support is in inactive position, a finger 20 mounted below the drill and above the lower of said guards, said finger being arranged to be engaged by the work upon the support for releasing the locking means, and a spring secured to said support arranged to return the support to 25 inoperative position.

12. In combination, a guide member movable by work applied to it and by such movement directing said work for an operation upon it, and means for locking the guide member against 30 such operating movement, said means being releasable by the work upon its application.

13. In combination, an operating tool, a guide member for the work movable under the influence of said work in co-operation with the tool, and 35 locking means for the member releasable by contact of the work therewith to permit operation of the tool upon said work.

14. In combination, a drill, a guard for the drill movable under the influence of the work, and

a lock for the guard, said lock being movable into and out of engagement with the guard and released during the application of the work.

15. In a machine for forming holes in the bottoms of lasted shoes, a base, a motor fixed 5 thereon, a drill rotatable by the motor, a slide movable upon the base longitudinally of the drill and provided with a work support having a surface by contact of the last cone with which the slide is moved, in which surface is an opening 10 through which the drill passes, and guard members extending from the contact surface of the support at opposite sides of the drill, the outer ends of the guard members being separated to receive between them the cone of a last held in 15 the hands of the operator and arranged to guide the cone into engagement with the contact surface of the work support.

16. In combination, a drill arranged to operate through the cone of a last, guard members extending at opposite sides of the drill and arranged to receive the last cone between them, said 20 guard members being supported to move together longitudinally of the drill, a lock for preventing such movement of the guard members, and 25 means for releasing the lock upon entrance of the work between the guard members.

17. In a machine for making holes in the bottoms of shoes, a drill, a contact member surrounding the drill and movable by the work 30 along said drill, and a locking member for the contact member movable under the influence of the work.

18. In a heel-seat drilling machine, a drill, a member mounted for movement by the work and 35 provided with an opening through which the drill extends, and locking means for the member releasable by contact of the work therewith.

FRANCIS LOW BRANDT.
